UNITED STATES PATENT OFFICE.

PHILEMON O. DICKINSON, OF NEWARK, NEW JERSEY.

DESIGN FOR A BRUSH-BACK, &c.

SPECIFICATION forming part of Design No. 24,902, dated November 19, 1895.

Application filed October 17, 1895. Serial No. 566,011. Term of patent 3½ years.

To all whom it may concern:

Be it known that I, PHILEMON O. DICKINSON, a citizen of the United States, residing at Newark, in the county of Essex and State 5 of New Jersey, have invented and produced a new and original Design for Backs and Handles of Brushes, Mirrors, and Similar Articles, of which the following is a description, reference being had to the accompanying drawing, which shows the back and handle of a mirror.

The general outline of the back is circular. At a little distance from the outline is arranged a circular border, which is composed 15 of the band A and recurrent and overlying designs B C D of the rococo order. Within this border is located the rococo-shield design E, the space between this design and the other designs being left plain.

20 The handle of the back consists of the an-

nular disk F, bearing the circularly-running ribbon G, and of the foliate scrolls H.

The essential features of the design of the back and of the design of the handle are those above set forth.

25

What is claimed as new is—

1. In the design herein set forth, the design for the back of a brush, mirror or similar article, substantially as shown and described.
2. In the design herein set forth, the design 30 for the handle of the back of a brush, mirror or similar article, substantially as shown and described.
3. The design for the back and handle of a brush, mirror or similar article, substantially 35 as shown and described.

PHILEMON O. DICKINSON.
